CARDBOARD DISH

Charles R. Pearce, Pittsburgh, Pa.

Application January 19, 1956, Serial No. 560,098

3 Claims. (Cl. 229—30)

This invention relates to cardboard dishes, and more particularly to those folded into shape from blanks.

It is among the objects of this invention to provide a dish which is folded from a single sheet of cardboard, which can be handled as a flat blank until ready for use, which can be quickly and easily formed into shape, which holds itself in shape without the use of fastening members, and which readily adapts itself to the shape of a ship.

According to this invention, the dish has a trough-like body provided with inclined side walls meeting at the bottom, and with triangular end walls. Lying flat against one-half of each end wall is an upright, inwardly extending, triangular reverse fold, the opposite sides of which are secured face-to-face. The reverse fold is integrally joined to the adjoining end wall along the center of that wall. Extensions of more or less triangular shape project lengthwise of the body away from the upper edges of each end wall and reverse fold. Side and end flaps extend downward from the upper edges of the side walls and the outer edges of the end wall extensions. The side flaps not only reinforce the body, but they also hold it upright.

The preferred embodiment of the invention is illustrated in the accompanying drawings, in which

Fig. 1 is a side view of my dish;

Fig. 2 is a plan view thereof;

Figs. 3 and 4 are end views;

Fig. 5 is a bottom plan view of the sheet from which the blank is formed;

Fig. 6 is a side view of the blank;

Fig. 7 is a view of the blank with one side removed;

Fig. 8 is a fragmentary plan view of one end of the blank when opened the first time;

Fig. 9 is an end view of Fig. 8;

Fig. 10 is a plan view of the opened blank refolded to its second position;

Fig. 11 is a side view of Fig. 10;

Fig. 12 is a side view of the blank with the flaps folded down;

Fig. 13 is a fragmentary side view of one end of the blank when opened the second time;

Fig. 14 is an end view of Fig. 13; and

Fig. 15 is a fragmentary plan view of the blank as shown in Fig. 13, but with the triangular projection folded back against the end wall.

Referring to Figs. 1 to 4, it will be seen that the dish has a trough-like body 1 or receptacle portion provided with inclined side walls 2 that meet at the bottom along the center of the dish. The end walls 3 of the body therefore are triangular. Inside the dish, half of each end wall is overlaid by a vertical triangular reverse fold 4, the opposite sides of which are joined face-to-face and are integral with the end wall along its center directly above the point where the side walls come together. Integral with the upper edges of the end walls and the upright reverse folds are extensions 6 and 7, respectively, of generally triangular shape which project more or less horizontally lengthwise of the dish away from its body.

2

The body is reinforced by side flaps 8 that extend down from the upper edges of its side walls. These flaps are at least as deep as the body, so that they form legs to hold the body upright. There also are end flaps 9 extending downward from the outer edges of end wall extensions 6. These flaps are continuations of the side flaps and hold the extensions down.

The side and end flaps may be cut to give the dish different appearances. They also may be decorated by printing to represent various objects. For example, when this dish is used for ice cream, it is desirable to have it represent a ship, so that a young consumer who has emptied the dish can brag that he sank a ship. In such a case, the side and end flaps can have port holes and anchors printed on them, and the end extensions will represent decks, from which removable flags or pennants 11 can be flown by inserting them in slits 12. If a battleship is desired, pictures of guns can be printed on the flaps.

The dish that has just been described is formed from a single sheet of cardboard by folding it into the shape shown. The sheet has the general shape of the one shown bottom side up in Fig. 5 when a dish is to represent a ship. The sheet has fold lines pressed into it, indicated by the broken lines, along which it can be folded easily. It will be seen that at opposite ends there are triangular areas 4a, 4b, 7a and 7b that have been coated on the bottom with an adhesive. To make the blank from which the dish is formed, the sheet is folded along its longitudinal center line and transversely across the ends of side walls 2 and side flaps 8 to provide a reverse fold at each end located between the flat rectangular sides of the blank, as indicated in Figs. 6 and 7. In doing this, triangular portions 4a and 7a are poined by the adhesive to triangular portions 4b and 7b to form reverse folds 4 and extensions 7. This is all done by the manufacturer, and it is this flat blank of Fig. 6 that is shipped to the retail store.

When it is desired to convert the flat blank of Fig. 6 into a dish or other receptacle, the opposite sides of the blank are spread apart, which has the effect of pulling the end walls and end flaps and extensions 6 out from between the side walls and into the position shown in Figs. 8 and 9, but the adhesively joined reverse folds continue to project toward each other. The blank is not left in this position, but the end walls and reverse folds are pulled farther away from each other and then the opposite sides of the blank are pressed back against each other as shown in Fig. 10. The blank then has the appearance from the side shown in Fig. 11. In other words, the end portions of the blank which projected between its opposite sides in Fig. 6, now project away from the ends of those sides.

The next step is to fold down the side and end flaps 8 and 9 as shown in Fig. 12. Following this, the blank again is opened to pull the end walls 3, extensions 6 and end flaps 9 up into the upright position shown in Figs. 13 and 14. The adhesively joined reverse folds at the opposite ends will then project toward each other again. The next step is to fold the reverse folds 4 over against half of each end wall 3, as shown in Fig. 15, which simultaneously folds each extension 7 against half of an end wall extension 6. At this point, end flaps 9 lie substantially flat against end walls 3, and side flaps 8 lie substantially flat against side walls 2.

The final step in setting up the dish is to bend extensions 6 and 7 outwardly and down to substantially horizontal positions, where they will be held by end flaps 9 and represent decks at the bow and stern of a ship. The dish or ship is now in the shape shown in Figs. 1 to 4 and is ready for use. It will be seen that when the end extensions are folded down in this manner, the side and end

flaps swing out away from the body of the dish into substantially upright position. The side flaps stiffen the body and serve as legs to hold it upright.

This dish is intended to be thrown away after it is used, and it is inexpensive enough for that purpose. The rectangular blanks of Fig. 6 are easy to ship and to handle because they are flat and can easily be packed or bundled. It requires only a few seconds to form the blank into a dish. No fastening members are required and no locking together of tongues and slots is necessary. The only adhesive that is used is applied by the manufacturer to the original flat sheet.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. A dish suitable for ice cream and folded into shape from a single sheet of cardboard, the dish having a trough-like body provided with inclined side walls meeting at the bottom and with triangular end walls, the center of each end wall having an upright inwardly extending triangular reverse fold lying flat against one-half of that end wall, means joining the opposite sides of said fold face-to-face, generally triangular extensions projecting lengthwise of said body away from the upper edges of each end wall and reverse fold, and side and end flaps extending downward from the upper edges of the side walls and the outer edges of said end wall extensions, the lower edges of the side flaps being located in a horizontal plane at the bottom of said body, whereby the body is reinforced and held upright by means of the side flaps.

2. A dish suitable for ice cream and folded into shape from a single sheet of cardboard, the dish having a trough-like body provided with inclined side walls meeting at

the bottom and with triangular end walls, the center of each end wall having an upright inwardly extending triangular reverse fold lying flat against one-half of that end wall, means joining the opposite sides of said fold face-to-face, generally triangular extensions projecting lengthwise of said body away from the upper edges of each end wall and reverse fold, and side and end flaps extending downward from the upper edges of the side walls and the outer edges of said end wall extensions, the lower edges of the side flaps being located in a horizontal plane at the bottom of said body, whereby the body is reinforced and held upright by means of the side flaps, said end flaps converging toward the opposite ends of the dish and having their outer lower corners cut away.

3. A dish suitable for ice cream and folded into the general shape of a ship from a single sheet of cardboard, the ship having a trough-like hull provided with inclined side walls meeting at the bottom and with triangular end walls, the center of each end wall having an upright inwardly extending triangular reverse fold lying flat against one-half of that end wall, means joining the opposite sides of said fold face-to-face, generally triangular extensions projecting lengthwise of said hull away from the upper edges of each end wall and reverse fold and forming a deck area, and side and end flaps extending downward from the upper edges of the side walls and the outer edges of said end wall extensions, the side flaps forming the opposite sides of the ship and their lower edges being located in a horizontal plane at the bottom of said hull, whereby the hull is reinforced and held upright by means of the side flaps, said end flaps converging toward the opposite ends of the dish and having their lower outer corners cut away to represent the bow and stern of the ship, and at least one of said deck areas being provided with an opening adapted to receive and frictionally support a flag or the like.
